UNITED STATES PATENT OFFICE.

ADOLPH RUBIN, OF ST. LOUIS, MISSOURI, ASSIGNOR, BY MEENE ASSIGNMENTS, TO ARCADE MANUFACTURING COMPANY, OF FREEPORT, ILLINOIS, A CORPORATION OF ILLINOIS.

FASTENER FOR REFRIGERATOR DOORS.

Application filed December 5, 1925. Serial No. 73,391.

This invention relates to refrigerator door fasteners of the general type described in my prior U. S. Patent No. 1,519,267, dated December 16, 1924, which comprise a latch 5 arranged so that it will clear the keeper when the refrigerator door is moving into its closed position, and thereafter will move automatically into interlocking engagement with the keeper.

10 The main object of my present invention is to provide a door fastener of the general type mentioned that is inexpensive to manufacture, and which is particularly adapted for use on small refrigerators such as are 15 used in homes or dwellings.

Another object is to provide a door fastener of the general type mentioned, which is of such design that many of the parts of same can be formed from sheet metal stampings. Other objects and desirable features 20 of my invention will be hereinafter pointed out.

Figure 1 of the drawings is a front elevational view of a refrigerator door fastener 25 constructed in accordance with my present invention.

Figure 2 is a side elevational view of said fastener, showing the latch in its depressed position in interlocking engagement with the 30 keeper which is shown in dotted lines.

Figure 3 is a view similar to Figure 2, showing the casing of the fastener in section and the latch in its elevated position or inoperative position.

35 Figure 4 is a detail view of the fastener, the trigger and the spring that is used for actuating said parts, the casing of the fastener being omitted, so as to more clearly illustrate the way said parts are arranged.

40 Figure 5 is a transverse sectional view, taken on the line 5—5 of Figure 4, looking in the direction indicated by the arrows, the casing of the fastener being shown in section.

Figure 6 is a detail sectional view, taken 45 on the line 6—6 of Figure 4, looking in the direction indicated by the arrows, showing the trigger in its inoperative position.

Figure 7 is a bottom plan view of the part shown in Figure 6; and

50 Figure 8 is a view similar to Figure 6, illustrating how the wedge-shaped end of the actuating spring shifts the trigger laterally into its operative position.

Referring to the drawings which illustrate the preferred form of my invention. A 55 designates the casing of the fastener which is adapted to be mounted on a refrigerator door α . B designates the latch which preferably consists of an oscillating member or pivotally mounted member arranged inside of the casing in such a way that a portion 1 at its free end projects laterally through a side opening in the casing. C designates the keeper which is adapted to be mounted on a stationary part of the refrigerator adjacent the side edge of the door α , so that it will co-operate with the portion 1 of the latch B to retain the refrigerator door in its closed position. D designates the handle of the fastener pivotally connected by a pintle pin 2 to forwardly-projecting ears 3 on the casing and provided with an angularly-disposed arm 4 arranged in a hole 5 in the latch B, as shown in Figure 4, thereby permitting the latch to be raised or moved upwardly 60 into its operative position by swinging the handle D forwardly. E designates as an entirety the trigger that is used to retain the latch in its elevated or inoperative position, and F designates a spring which normally exerts pressure on the latch B in a direction tending to move it downwardly and which is combined with the trigger E 65 in such a manner that it moves said trigger into operative relationship with the latch B 70 whenever the handle D is actuated to raise the latch. In order that the trigger E will be automatically disengaged from the latch, after the portion 1 on the latch has cleared the keeper C, when the refrigerator door is moving into its closed position, the trigger E is provided with a tripping device 75

80 which is so arranged that it strikes against an abutment 7 on the keeper C just before the refrigerator door reaches its closed position, the further movement of the door causing the abutment 7 to exert pressure on the tripping device 6 in a direction to disengage the trigger E from the latch and thus permit the portion 1 on the latch to move downwardly into interlocking engagement with the keeper C through the influence of the spring F. 85 In my present door fastener the trigger E is formed by a horizontally-disposed lever 90

95

100

105

arranged under the latch B, as shown in Figure 4, and provided adjacent its free end with an upwardly-projecting arm 8 disposed so that it will lie in a vertical plane 5 at one side of the latch B when said latch is in its depressed position and when said trigger is in its inoperative position, said arms lying in the same vertical plane as the latch when said latch is in its raised 10 or operative position and when said trigger is in its operative position. The means that is used to swing the trigger E laterally so as to move the arm 8 thereon into and out of operative relation with the latch B 15 consists of a wedge or tapered member 9 formed preferably by one end portion of the spring F and arranged between the trigger E and an abutment formed by an inclined surface 10 that is stationary with reference 20 to said trigger. The spring F is substantially C-shaped in general outline and is arranged with its upper end portion in engagement with the top side of the latch B and its lower end portion, which carries 25 the wedge 9, in engagement with the trigger E and the stationary inclined abutment 10 that is arranged at one side of said trigger. When the refrigerator door is in its closed position the spring F holds the latch 30 B depressed. At this time the upwardly-projecting arm 8 on the trigger E lies at one side of the latch between said latch and the front wall of the casing of the lock, and the wedge 9 on the lower end of the 35 spring F engages the trigger E and the stationary inclined surface 10, as shown in Figure 6. When the handle D is actuated to raise the latch, the upward movement of the latch increases the tension of the 40 spring F, or moves said spring in such a way that the wedge 9 thereon moves upwardly between the stationary inclined surface 10 and the trigger E, thus causing said trigger to swing laterally in a direction 45 to move the upwardly-projecting arm 8 thereon into operative position beneath the latch B. So long as the trigger remains in this position, the latch B remains in its elevated position. Consequently, when 50 the refrigerator door moves towards its closed position, the portion 1 on the end of the latch will clear the keeper C, and just before the refrigerator door reaches its fully closed position, the tripping device 6 on 55 the trigger strikes against the stop 7, with the result that the arm 8 on the trigger is automatically disengaged from the latch, which latch thereafter moves downwardly 60 into engagement with the keeper under the influence of the spring F. The particular shape or form of the wedge 9 is immaterial, so long as it be pointed or tapered and arranged to move between a portion of the trigger E and a stationary member or abut- 65 ment which is disposed in such relation

with the trigger that the movement of said tapered or pointed element between said parts will cause the trigger to swing laterally in a direction to cause the arm 8 thereon to hold the latch B in its inoperative 70 position. I prefer, however, to make the trigger operating member 9 in the form of a flat wedge that constitutes the lower terminal portion of the spring F and provide the trigger E with a notch 11, as shown 75 in Figure 7, that extends inwardly from one of the side edges of said trigger, so as to receive the wedge 9, thereby permitting said parts to be compactly arranged, and hence, making it well adapted for use on small 80 refrigerators, such as are used in homes. The part 10 previously referred to as a stationary inclined surface is disposed oppositely to the notch 11 in the side edge of the trigger E, and while I prefer to construct said part 10 in the form of an inclined surface, this is not absolutely essential, although an inclined surface is desirable, in that it provides a bearing surface of relatively great area for one of the inclined faces of the wedge 9. The essential thing is that the pointed or tapered member 9 be interposed between a stationary part 10 and the trigger E in such a way that when said tapered member 9 moves upwardly into the position shown in Figure 8, it will cause the trigger E to swing laterally.

In the form of my invention herein illustrated the latch B consists of a sheet metal stamping of substantially channel shape in cross section whose end portion 1 is swaged or pressed in such a way as to form a substantially tubular member that co-operates with the keeper C, said latch being oscillatingly mounted on a pivot pin 12 on the inside of the casing A that is connected to the front wall of said casing. In order that the latch will be held spaced away from the front wall of the casing A, thus providing a space for the upwardly-projecting arm 8 on the trigger E, the pivot pin 12 is provided with a shoulder or enlarged portion 12a, as shown in Figure 5. The particular manner in which the trigger E is mounted is also 115 immaterial, so far as my broad idea is concerned. I prefer, however, to arrange a supporting member G inside of the casing A of the fastener and connect one end of the trigger E to an angularly-disposed flange 13 on 120 said supporting member by means of a pintle pin 14, the stationary part 10 previously referred to against which the wedge 9 bears being integrally connected to said flange 13, as shown in Figure 4. The supporting member G is sustained at one end by the pivot pin 12 which is made long enough so that it will project through said supporting member, as shown in Figure 5, and the opposite end of said supporting member G is 130

provided with an integral latch guide 15 that is positioned in an opening in the side wall of the casing A. In most instances said opening will consist of a notch in the side 5 wall of the casing, and movement of the latch guide 15 relatively to said side wall will be prevented by lugs 15^a on said latch guide that are seated in depressions in the top and bottom edges of said notch. The 10 tripping portion 6 of the trigger E projects forwardly through the latch guide 15 of the supporting member G, and if desired, said supporting member can be provided with one or more horizontally-disposed portions 15 16, as shown in Figure 4, that serve as a guide or bearing surface for the trigger E to slide upon when said trigger is shifted laterally into and out of operative position. In assembling the parts of the fastener the 20 trigger E is first pivotally connected to the supporting member G and said supporting member and the latch B are then slipped over the pivot pin 12 which projects inwardly from the front wall of the casing A 25 of the lock. The end of said pivot pin 12 is then upset, as shown in Figure 5, so as to hold said parts in operative relationship, the opposite end portion of the supporting member G being interlocked with the side 30 wall of the casing by the lugs 15^a on the latch guide 15 which were inserted in the recesses in the casing provided for same before the supporting member G was slipped over the pivot pin 12. The final step in the 35 assembling operation is to insert the wedge-shaped lower end portion 9 of the spring F in the notch 11 in the trigger E and then snap the upper end portion of said spring into a hole provided for same in the top side 40 of the latch B.

A refrigerator door fastener of the construction above described is inexpensive to manufacture, due to the fact that most of the elements of same can be formed from 45 sheet metal stampings and it is reliable in operation and can be used for small household refrigerators, because the co-operating parts of same are of rugged designs and are compactly arranged, and the means that is 50 used to actuate both the latch and the trigger consists of a very stiff C-shaped spring F.

Having thus described my invention, what I claim as new and desire to secure by Letters Patent is:

55 1. A refrigerator door fastener provided with a latch, means for disengaging said latch from the keeper, a movable trigger for holding said latch in an inoperative position, and a substantially C-shaped spring 60 combined with said latch and trigger for moving both of said elements to render them operative.

2. A refrigerator door fastener provided 65 with a latch, means for disengaging said latch from the keeper, a shiftable trigger

provided with a portion that is adapted to move into and out of the plane of the latch, a tapered member for actuating the trigger, and a spring combined with said latch and with said tapered member in such a way as 70 to cause said tapered member to move the trigger into an operative position when the latch is disengaged from the keeper.

3. A refrigerator door fastener provided with a pivotally mounted latch, means for 75 disengaging said latch from the keeper, a trigger for holding said latch in an inoperative position, an abutment, a pointed member adapted to be moved between said abutment and trigger to render the trigger operative, and means for causing said pointed member to actuate the trigger when the latch is disengaged from the keeper.

4. A refrigerator door fastener provided with a pivotally mounted latch, means for 85 disengaging said latch from the keeper, a pivotally mounted trigger arranged adjacent said latch and provided with a portion that is adapted to move into the plane of the latch, an abutment arranged adjacent the 90 trigger, a wedge that is adapted to move between said abutment and trigger to render the trigger operative, and a spring combined with said latch and wedge for causing said wedge to operate and for causing the 95 latch to move into engagement with the keeper when the trigger is rendered inoperative.

5. A refrigerator door fastener provided with a pivotally mounted latch, means for 100 disengaging said latch from the keeper, a pivotally mounted trigger provided with a portion that is adapted to move into and out of the plane of the latch, an abutment adjacent said trigger, and a substantially 105 C-shaped spring having one of its ends arranged in engagement with the latch and provided at its opposite end with a wedge that is adapted to be forced between the abutment and trigger when the latch is disengaged from the keeper.

6. A refrigerator door fastener provided with a pivotally mounted latch, means for 115 disengaging said latch from the keeper, a pivotally mounted trigger adjacent the latch that swings at substantially right angles to the latch, a portion on said trigger that is adapted to hold the latch inoperative when said trigger swings in one direction, and a substantially C-shaped 120 spring having its upper end portion engaged with the latch and provided at its lower end portion with a wedge that causes the trigger to swing laterally into an operative position when the latch is disengaged 125 from the keeper.

7. A refrigerator door fastener provided with a pivotally mounted latch, means for 130 disengaging said latch from the keeper, a pivotally mounted trigger arranged to swing

at substantially right angles to the latch and provided with a portion that is adapted to engage and hold it in an inoperative position, a stationary, inclined member arranged adjacent said trigger, a notch in one edge of said trigger, and a substantially C-shaped spring, arranged with one of its ends in engagement with the latch and provided at its opposite end with a wedge positioned 10 in the notch in the trigger and arranged in engagement with said inclined surface.

8. A refrigerator door fastener, comprising a casing, a pivotally mounted latch inside of said casing provided with a portion 15 that projects laterally through the casing, a handle on the exterior of the casing for disengaging said latch from the keeper, a supporting member inside of the casing provided with a guide for the latch, a trigger 20 pivotally connected to said supporting member and provided with a member adapted to move into and out of the plane of the latch, and an actuating member adapted to move between the trigger and a portion of said 25 supporting member to swing the trigger laterally into an operative position when the latch is disengaged from the keeper.

9. A refrigerator door fastener, comprising a casing, a pivotally mounted latch in 30 said casing, a handle for disengaging said latch from the keeper, a supporting member inside of the casing provided with a guide for the latch, means for interlocking said 35 guide with the casing, a pivotally mounted trigger on said supporting member arranged to swing at substantially right angles to the latch and provided with a portion for holding the latch in an inoperative position, and a substantially C-shaped spring for rendering 40 the latch operative and for causing the trigger to swing laterally into an operative position when the latch is disengaged from the keeper.

10. A refrigerator door fastener, comprising 45 a casing, a pivot pin carried by said casing, a latch oscillatingly mounted on said

pivot pin and provided with a portion that projects laterally through the side wall of the casing, a handle on the exterior of the casing for disengaging said latch from the keeper, 50 a supporting member inside of the casing supported at one end by said pivot pin, a latch guide on the opposite end of said supporting member that is interlocked with the casing, a pivotally mounted trigger on said supporting member arranged to swing at substantially right angles to the latch and provided with a portion for holding the latch in an inoperative position, and a substantially C-shaped spring arranged with 55 one of its ends in engagement with said latch and provided at its opposite end with a wedge that is adapted to be forced between the trigger and said supporting member to swing the trigger laterally into an 60 operative position.

11. A refrigerator door fastener, comprising a casing, a pivot pin inside of said casing, a pivotally mounted latch on said pivot pin provided with a portion that projects 70 laterally through the side wall of the casing, a handle on the exterior of the casing for disengaging said latch from the keeper, a supporting member inside of the casing supported at one end by said pivot pin and 75 provided at its opposite end with a latch guide that is interlocked with the casing, a trigger pivotally mounted on said supporting member under the latch, an arm on said trigger that is adapted to hold the latch in 80 an inoperative position, a tripping device on said trigger that projects laterally through the latch guide, a notch in one edge of said trigger, an inclined surface on said supporting member arranged adjacent said 85 notch, and a substantially C-shaped spring arranged with its upper end in engagement with the latch and provided at its lower end with a wedge positioned in said notch and arranged in engagement with said inclined 90 surface.

ADOLPH RUBIN.
